US0D1084845S

(12) **United States Design Patent** (10) **Patent No.:** **US D1,084,845 S**
(45) **Date of Patent:** **** Jul. 22, 2025**

(54) **CONTAINER**

(71) Applicant: **STASHER, INC.**, Emeryville, CA (US)

(72) Inventor: **Angelo Carpinelli**, Emeryville, CA (US)

(73) Assignee: **Stasher, Inc.**, Emeryville, CA (US)

(**) Term: **15 Years**

(21) Appl. No.: **29/939,248**

(22) Filed: **Apr. 25, 2024**

Related U.S. Application Data

(63) Continuation of application No. 29/860,291, filed on Nov. 17, 2022, now Pat. No. Des. 1,030,472.

(51) **LOC (15) Cl.** **09-05**

(57) **CLAIM**

The ornamental design for a container, as shown and described.

DESCRIPTION

FIG. 1 is a top, front, and right side isometric view of a container according to the present design;

FIG. 2 is an isometric view of a bottom, rear, and left side of the container of FIG. 1;

FIG. 3 is a front elevational view of the container of FIG. 1; FIG. 4 is a rear elevational view of the container of FIG. 1; FIG. 5 is a left side elevational view of the container of FIG. 1;

FIG. 6 is a right side elevational view of the container of FIG. 1;

FIG. 7 is a top plan view of the container of FIG. 1; and, FIG. 8 is a bottom plan view of the container of FIG. 1. The dash-dash lines are included for the purpose of illustrating portions of the container that form no part of the claimed design. The oblique shade lines depict a transparent or translucent surface or material.

1 Claim, 8 Drawing Sheets
